UNITED STATES PATENT OFFICE

2,496,166

DOOR CHECK AND CLOSER

Martin W. Keller, Pine Bluff, Ark., assignor of thirty-three and one-third per cent to Ben Pearson and thirty-three and one-third per cent to Shaffer Haley, both of Pine Bluff, Ark.

Application August 11, 1947, Serial No. 767,914

4 Claims. (Cl. 16—57)

1

The present invention relates to new and useful improvements in door checks and more particularly to a combined door check and closer embodying means whereby the door is closed by a pulling action.

Heretofore it has been the usual practice to provide door checks and closers which exert a pushing force on the door which have a tendency to cause the door to close rapidly during its initial closing action and then abruptly stopping, and which subjects the hinges to a severe strain and frequently results in damage to the door proper.

Accordingly, it is an object of the present invention to provide a combined door check and closer which exerts a pulling-closing action on the door and which is constant throughout its entire closing movement.

A still further object is to provide a device of this character of simple and practical construction, which is efficient and reliable in operation, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the combined door check and closer mounted in position on a door;

Figure 2 is a top plan view on a reduced scale;

Figure 3 is an enlarged longitudinal sectional view;

Figures 4 to 7, inclusive, are transverse sectional views taken respectively on the lines 4—4, 5—5, 6—6 and 7—7 of Figure 3; and

Figure 8 is an enlarged group perspective view of the piston, check plate and cage therefor.

Referring now to the drawings in detail wherein for the purpose of illustration, I have disclosed a preferred embodiment of the invention, the numeral 5 designates a cylinder which is closed at one end and provided with a cap threaded on its opposite end.

A vertical pivot pin 7 rises from the top of the closed end of the cylinder and which is pivotally held in an attaching plate 8 for horizontal swinging movement of the cylinder 5.

A cylindrical reservoir 9 is supported in a longitudinally extended position on top of the cylinder 5 by means of a boss 10 at one end of the

reservoir and a neck 11 at its opposite end which provides communication for the rear end of the cylinder 5 with the reservoir. The top of the reservoir is provided with a vent opening 12.

5 A piston rod 13 is slidably mounted in a neck 14 carried by the cap 6 and a packing gland 15 is threaded on the neck to seal the piston rod.

A piston 16 is integrally formed with the inner end of the rod 13 and has a working fit in the cylinder 5. A plurality of apertures 17 are formed in the piston and over which a substantially clover leaf check plate 18 is held in position by a cage 19 suitably secured to piston 16. The check plate is provided with openings 20 aligned with the openings 17 and of a diameter or size substantially less than the openings 17. The cage 19 includes leg portions 21 positioned between the projections of the check plate to prevent rotation of the check plate and thus keep the openings 20 in alignment with the openings 17.

A bracket 22 is clamped to the outer portion of the piston rod 13 and includes laterally projecting arms 23, to the ends of which the rear end of coil springs 24 are hooked, the front ends of the springs being attached to hooks 25 secured to the opposite sides of the cylinder 5 adjacent its front end, the springs exerting an influence on the piston and piston rod to move the piston inwardly toward the front end of the cylinder.

20 A rubber cushion 26 is secured to the inner side of the cap 6 for contact by the piston 16 during the outward movement of the piston rod to reduce shock.

25 35 The rear end of the piston rod 13 is formed with an opening 27 through which a pin 28 carried by an attaching bracket 29 is inserted to provide a pivotal connection for the rear end of the piston rod.

40 In the operation of the device, the attaching plate 8 is secured to the under side of a door frame 30 while the bracket 29 is secured to a door 31. The plate 8 is attached to the door frame adjacent the hinged edge of the door, and accordingly, during opening movement of the door, the piston rod 13 and piston 16 are moved outwardly and liquid, such as oil or the like contained in the cylinder 5 is partially forced into the reservoir 9 through the neck 11 and the remainder passing through the openings 17 behind the piston. During rearward movement of the piston, the check plate 18 moves away from the piston to prevent obstruction of the passage

45 50 55 of fluid to the front end of the cylinder.

55 The opening of the door is thus not restricted

or retarded by the door check and closer except by the placing of the springs 24 under tension.

When the door is released, the springs will exert their influence on the door to close the same by a pulling action on the door, the closing movement of the door moving the piston and piston rod inwardly. The check plate 18 is then moved against the piston 16 to substantially close the openings 17, and the relatively small openings 20 in the check plate allow the liquid to slowly pass to the rear end of the chamber 5 to thus retard the closing of the door at a uniform closing speed.

The size of the openings 20 determines the speed of the closing movement of the door.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A door check comprising a cylinder having a piston working therein, said cylinder being attached at one end to a stationary structure and said piston including a piston rod projecting from an opposite end of the cylinder and attached to a door, said piston having an opening therethrough for the passage of fluid in the cylinder from one end to the other during movement of the piston, and means carried by the piston to retard the fluid during movement of the piston in one direction, said means comprising a check plate having an opening therein of a size relatively smaller than that of the opening in the piston and movable into and out of position at one side of the piston during opposite movements of the piston and a cage carried by the piston for the check plate.

2. A door check comprising a cylinder having a piston working therein, said cylinder being attached at one end to a stationary structure and said piston including a piston rod projecting from an opposite end of the cylinder and attached to a door, said piston having an opening therethrough for the passage of fluid in the cylinder from one end to the other during movement of the piston, and means carried by the piston to retard the fluid during movement of the piston in one direction, said means comprising a check

plate having an opening therein of a size relatively smaller than that of the opening in the piston and movable into and out of position at one side of the piston during opposite movements of the piston and a cage carried by the piston for the check plate and including means for holding the openings in alignment with each other.

3. A door check comprising a cylinder having a piston working therein, said cylinder being attached at one end to a stationary structure and said piston including a piston rod projecting from an opposite end of the cylinder and attached to a door, said piston having an opening therethrough for the passage of fluid in the cylinder from one end to the other during movement of the piston, and means carried by the piston to retard the fluid during movement of the piston in one direction, said means comprising a check plate having an opening therein of a size relatively smaller than that of the opening in the piston and movable into and out of position at one side of the piston during opposite movements of the piston and a cage carried by the piston for the check plate and including guide means to maintain the openings in alignment.

4. A door check comprising a cylinder having a piston working therein, said cylinder being attached at one end to a stationary structure and said piston including a piston rod projecting from an opposite end of the cylinder and attached to a door, said piston having an opening therethrough for the passage of fluid in the cylinder from one end to the other during movement of the piston, and means carried by the piston to retard the fluid during movement of the piston in one direction, said means comprising a check plate having an opening therein of a size relatively smaller than that of the opening in the piston and movable into and out of position at one side of the piston during opposite movements of the piston, and a cage carried by the piston for the check plate and including legs forming guides for the edges of the check plate to maintain the openings in alignment.
